UNITED STATES PATENT OFFICE.

GEORGE V. HOUSE, JR., OF NEW YORK, N. Y.

DESIGN FOR A TRUSS-WEBBING.

SPECIFICATION forming part of Design No. 19,905, dated June 17, 1890.

Application filed May 1, 1890. Serial No. 350,204. Term of patent 14 years.

To all whom it may concern:

Be it known that I, GEORGE V. HOUSE, Jr., a citizen of the United States, and a resident of New York, in the county and State of New York, have invented and produced a new and original Design for Truss-Webbing, of which the following is a full, clear, and exact description.

My invention relates to the embellishment of woven fabric, known as "webbing," which is specially employed as a material in the manufacture of trusses; and to illustrate my special design for this purpose reference is made to the accompanying drawing, forming a portion of this specification, and to the designating words and letters marked thereon.

Over the entire surface of the material there is a diagonal or bias-ribbed appearance, which is the ground or basis of the design.

The ornamental portion of the design, which constitutes the leading feature of the same, consists in six parallel stripes of varying colors *a b c d e f* on each edge portion of the webbing, slightly within the selvage edges of the same.

Having described my invention, I claim as new and desire to secure by Letters Patent—

The design for truss-webbing herein shown and described, consisting of a basis of one color having a bias-ribbed appearance and six stripes *a b c d e f* of various colors near the selvage edges of the webbing.

GEORGE V. HOUSE, JR.
